DUPLICATING MACHINE AND METHOD

Ernest M. Terry, Harrison, N. Y.

Application December 2, 1935, Serial No. 52,508

4 Claims. (Cl. 101—132)

This invention relates to the method or process of duplicating printed, written or drawn records made on master copies with copying ink.

In duplicating processes and machines such as 5 are the subject of the invention herein, it is customary to moisten a clear sheet of copying paper with a suitable solvent and to pass such moistened sheet through a compressing medium which process deposits upon the moistened clear sheet a 10 portion of the copying ink from a master copy which passes simultaneously through the compressing medium and in contact with the clear sheet. The machines and processes heretofore developed have several undesirable features.

15 The methods for moistening the clear sheets do not provide effective control of the amount of liquid deposited and, therefore, furnish non-uniform distribution of solvent and consequent unevenness of duplication. The methods and machines heretofore developed do not permit complete operation from a single operator's position. When a new master copy is to be mounted, the operator must do so from the rear of the machine. In addition, many of the existing devices moisten 20 and print upon the underside of the clear sheet, ejecting the reproduction face down. If the sheet is not completely dry the characters may blur.

25 Some of the objects of my invention are to eliminate the undesirable features of the preceding paragraph and to provide means for uniform moistening of the upper face of the clear sheet and means for mounting the master from the ordinary operator's position.

Other objects of my invention will appear in 30 the detailed description herein and the drawings which accompany the same and in which drawings,

Fig. 1 is a top view of my duplicating machine;
Fig. 2 is a side elevation and shows the general 35 arrangement of the parts thereof;

Fig. 3 is an enlarged partial end detail view of the moistening fluid tank and associated parts;

Fig. 4 is a similar side elevation view;

Fig. 5 is an enlarged top detail view of the 40 master copy holding mechanism;

Fig. 6 is a similar side elevation view;

Fig. 7 is an enlarged side elevation detail view of the pressure roller and associated elements;

Fig. 8 is a similar end elevation view; and

Fig. 9 is a sectional detail view of the pressure 45 bar catch.

In the drawings elements 10 and 11 are the side 50 mounting plates of the stationary frame in which the various parts of the duplicating machine are mounted. The mounting plates are held in posi-

tion by means of rods 12, nuts 13 and bosses 29 on tank 27 which tank contains a moistening fluid such as alcohol.

Element 14 is the platen or drum upon which the master copy is mounted. Clamp 44 is arranged so that it may be raised against the tension of spring 43 and a master inserted and clamped in place. Pin 47 in clamp 44 and pin 46 in shaft 15 about which drum 14 rotates serve as means for fastening spring 43. Clamp 44 may 10 be raised by inserting special pins in openings 48 and exerting pull against spring 43. Gear 16 is fastened to drum 14 and is driven by gear 20 which in turn is rotated by the operation of lever 21 and knob 22. Element 17 is a spring click arrangement inserted in mounting plate 11 so that a pin fastened to drum 14 will engage said click when said drum reaches the end of its cycle. Screw 19 is mounted to an arrangement within drum 14 to permit changing the relative positions 20 on shaft 15 of drum 14 and gear 16. Pin 18 is located in the end surface of drum 14 so that it engages cam lever 23 at the end of the printing cycle.

Cam lever 23 is pivoted on shaft 25 and is retained at its position with stop 24 pressed against moistening pad 30 by means of spring 26. Pad 30 which is made of a porous and absorbent material such as felt is in contact at one end with pad 31 which is made of a similar material. Pad 31 is fastened to absorbent cords 32 which protrude into the solution in tank 27 through openings in the top. The moistening solution in tank 27 is poured therein through an opening ordinarily closed by cap 33. Tank cover 28 encloses the tank, moistening cords, etc. and is held in place by means of pins 45 and spring clamp 55.

Pressure adjusting lever 34 is fastened to shaft 49 at the midpoint of which is also fastened lever 37. The angular locations of both levers 34 and 40 37 upon shaft 49 may be altered by means of set screws 38. Lever 37 presses upon the center of cross bar 39 at both ends of which are mounted pins 41 which engage with bearings 50 movably located in guides 42. Roller 40 rotates in bearings 50 and is driven by friction with drum 14. Element 36, constructed of parts 36, 361, and 362, is a click pin arrangement which engages with element 35 so that lever 34 may be retained at any desired position within the arc of element 35. 50

Platform 51 serves as a guide for feeding the clear paper into the machine and is retained in its horizontal position by means of support 52. Element 53 is the platform upon which the duplicate print is ejected upon the completion of the 55

printing cycle. Platform 54 is an extension of platform 51.

The sequence of operations is as follows. Tank cover 28 and caps 33 are removed permitting 5 tank 27 to be filled with moistening fluid. The fluid is absorbed by capillary action in cords 32 and carried by gravity to pads 31 and 30. The reverse master is placed upon the horizontal surface of cover 28 after caps 33 and said cover are 10 replaced and the end of the master guided into place under clamp 44 so that the inked face is outward. Drum 14 is given one revolution by rotating lever 21 twice, the ratio of gears 16 and 20 being 2 to 1, thereby putting the master copy 15 in place. Screw 19 is loosened and the relative angular positions of gear 16 and drum 14 adjusted so that when the cycle starts from click arrangement 17 the clear paper will advance to the correct position in contact with the master 20 copy.

As drum 14 rotates pin 18 approaches cam lever 23 and depresses said lever until the click position is reached when the pin is at the furthestmost counterclockwise point of the cam surface. At this point pressure bar 24 is slightly 25 below pad 30 permitting a clear sheet to be inserted to make contact with the master at the common tangent point of drum 14 and roller 40.

Lever 34 is depressed until the required pressure is transmitted to roller 40 by means of shaft 49, lever 37, bar 39, pins 41 and bearings 50. This pressure may be altered at any time during the operation of the machine to alter the ink deposit upon the clear moistened paper.

35 The operator then rotates lever 21, by grasping knob 22, in a clockwise direction. A slight movement carries pin 18 from lever 23 and permits bar 24 to rise and press the clear sheet upon pad 30 causing said clear sheet to be moistened.

40 The amount of moisture deposited is initially determined by the number of cords 32 employed. The pressure between roller 40 and drum 14 draws the clear sheet towards platform 53 and in contact with the master. Said pressure causes the 45 master to deposit a definite amount of copying ink upon the clear sheet, thus reproducing the master figures or designs. At the completion of the drum cycle the imprinted sheet is ejected face upward upon platform 53.

50 When the operator has completed the work cover 28 may be removed and pad 31 swung up and placed on top of tank 27. This prevents a

surplus of moisture accumulating in pads 31 and 30. As operation is about to be recommenced pad 31 is replaced and a few moments will suffice to properly moisten pad 30.

The disclosure herein illustrates a preferred embodiment of my invention. It is obvious that other details could be substituted at various points in the machine. For instance, if it is not desired to prevent moisture accumulation and it is satisfactory to remove excess moisture by running several clear sheets without a master, pads 30 and 31 could be combined. This and other possible changes or additions would merely be alternative means of accomplishing the objects of my invention, specifically pointed out in, and limited only by the appended claims. 5 10 15

I claim:—

1. In a duplicating machine of the character described, a tank containing solvent, means for maintaining a uniform and constant capillary flow of said solvent to the upper face of the clear sheet consisting of absorbent pads and absorbent cords controlling the flow of said solvent, means for conveying the moistened clear sheet into contact with a reverse master copy and means for compressing the moistened clear sheet against the master copy to obtain a duplicate copy upon said moistened clear sheet. 20 25

2. The method of multiplying copies comprising the forming of a master copy with copying ink in reverse, moistening the upper face of a clear sheet by means of capillary flow through absorbent cords to absorbent pads in contact with said upper face, conveying said moistened clear sheet into contact with the reverse master copy 35 and compressing said moistened clear sheet against the master copy to obtain a duplicate copy upon said moistened clear sheet.

3. In a duplicating machine of the character described, a tank containing solvent, means for maintaining a uniform and constant capillary flow of said solvent to the upper face of the clear sheet consisting of absorbent pads and absorbent cords. 40

4. In a duplicating machine of the character described, a tank containing solvent, absorbent cords immersed therein and passing through said tank above the solvent level, and absorbent pads moistened by said absorbent cords and in contact with the upper face of the clear sheet. 45 50

ERNEST M. TERRY.
